INVENTOR
Mitchell Leventhal,
BY

Abraham Engel
ATTORNEY

UNITED STATES PATENT OFFICE

MITCHELL LEVENTHAL, OF BROOKLYN, NEW YORK, ASSIGNOR TO SOSY, INC., OF NEW YORK, N. Y., A CORPORATION OF NEW YORK

LOCK

Application filed October 3, 1929. Serial No. 397,002.

The present invention relates to locks primarily designed for use on suit-cases and the like, and aims to provide certain improvements therein.

5 An object of the present invention is to provide a relatively flat lock which is simple and sturdy in construction and which admirably lends itself to mass production.

Another object of the invention is to provide a lock of the spring pressed draw-bolt type wherein the draw-bolt serves the additional function of a housing or casing for the other operative elements of the lock.

A still further object of the invention is 15 to provide a lock wherein the rear housing plate, which is made of relatively thin metal, is formed with an integrally projecting latching lip which is displaced out of the face planes of the plate and bent back upon itself 20 to provide a double thickness of the metal so as to render said lip of requisite strength.

A still further object of the invention is to provide a suitcase lock or the like in which the tumbler is disposed and movable relatively 25 longitudinally to the draw-bolt, whereby the lock can be made much narrower than is now practical without detracting from its sturdiness.

The invention also embodies other features 30 of novelty and combinations of elements, all of which will be apparent from the detailed description that follows, reference being had to the accompanying drawings, wherein:

Figure 1 is a face view of a lock embodying my invention.

Fig. 2 is a rear view of the cover plate of the lock.

Fig. 3 is a longitudinal section of the lock taken substantially along the broken line 40 3-3 of Fig. 4.

Fig. 4 is a longitudinal section taken substantially along the plane of the line 4-4 of Fig. 3.

Fig. 5 is a section taken along the plane of 45 the line 5-5 of Fig. 4.

Fig. 6 is an elevation of the inside face of the draw-bolt.

Fig. 7 is a perspective view of the lock tumbler.

50 Referring to the drawings, let A indicate

the cover plate which may have any desired contour and preferably is formed with a rearwardly directed flange *a* extending completely about its perimeter. Struck up from the face of the cover plate and extending rearwardly thereof at substantially a right angle is a lip *a'* formed with a perforation *a* through which the tongue of the draw-bolt is adapted to pass to engage the lock ring of a hasp B. Substantially centrally of the plate there is formed three openings *a*², *a*³ and *a*⁴; the opening *a*² is a clearance opening for the key, and the openings *a*³ and *a*⁴ are adapted to receive therethrough lugs *c* and *c'* depending from an escutcheon C, which is mounted for limited sliding movement over the face of the plate A. In proximity to the lower edge of the plate it is provided with a struck-up inwardly directed hook-like lip *a*⁵ and an inwardly directed lip *a*⁶, the functions for which will be apparent as the description proceeds.

Mounted for sliding engagement with the back of the cover plate is a draw-bolt D having inturned longitudinal edge flanges *d*, *d*, in engagement with said cover plate. The draw-bolt D at one end is provided with a reduced longitudinal tongue which is depressed out of the planes of the faces of the draw-bolt, as shown at *d*² and said tongue is bent back upon itself to provide a double thickness of metal, as shown at *d*², the inner face of said bent back tongue being in sliding engagement with the back of the cover plate, all of which is best shown in Fig. 3. The end of the tongue *d*' at the bend or fold is tapered or bevelled as shown at *d*³ to facilitate its cooperative engagement with the hasp. The draw-bolt D is also formed with inwardly directed struck-up lips *d*⁴ and *d*⁵; and an outwardly pressed or struck-up portion providing a recess *d*⁶ at the edge of the draw-bolt opposite to that provided with the tongue. Also formed in face of the draw-bolt are perforations *d*⁷, *d*⁸, *d*⁹, and *d*¹⁰. The lips *d*⁴ and *d*⁵ are adapted to cooperate with the left hand flange *d* to guide a tumbler E in its movements. The recess *d*⁶ is adapted to house a coil spring *d*¹¹. Perforations *d*⁷ and *d*⁸ receive therethrough the lugs *c* and *c'* of the

escutcheon, which lugs are bent down over the outer face of the draw-bolt as shown at d^{12} to connect the draw-bolt and escutcheon together so that said elements will be movable as a unit. Perforation d^9 is a clearance for the end of the key. Perforation d^{10} which is of substantially U-shape in form provides the draw-bolt with a pin-like lip d^{13} , in alignment with the axis of recess d^6 , said lip d^{13} being adapted to engage within the end convolutions of spring d^{11} , while the convolutions at the opposite end of the spring are adapted to engage over the hook-like lip a^5 on the cover plate.

15 The tumbler E is preferably in the form of a flat metal stamping having parallel edges e , e' , the latter terminating in a shoulder e^2 . Formed along one edge of the tumbler is a number of detents e^3 , e^4 and e^5 . The detent e^3 is adapted to receive the bit of a key F and the detents e^4 and e^5 are adapted to engage the struck-up lip d^5 of the draw-bolt to lock the tumbler therewith so that both the draw-bolt and the tumbler will be movable as a unit. A flat leaf spring e^6 is secured in a kerf e^7 in the tumbler and said spring is adapted to bear against the left hand flange d so as to maintain the tumbler in spring pressed engagement with the lip d^5 .

20 From the assembly of the lock parts as shown in Figs. 3 and 4, it will be apparent that the draw-bolt D in its assembled relation on the cover plate incloses the tumbler E, the tumbler spring e^6 and the draw-bolt spring d^{11} and hence constitutes a housing for said elements.

In the operation of the lock the spring d^{11} normally holds the draw-bolt projected upwardly through the opening a in the lip a' , in which position it is adapted to latch the hasp B. When the tumbler is in the full line position shown in Fig. 4 the draw-bolt may be retracted or moved downwardly against the tension of the spring d^{11} , in which movement it carries with it the tumbler E as above explained. When the key F is turned to move the tumbler to the dotted line position, further movement of the tumbler in said direction is arrested by its engagement with the lip a^6 on the cover plate and in view of the engagement of the lip d^5 in the detent e^5 the draw-bolt will then be prevented from moving downwardly and will be locked in latching position.

55 From the foregoing description it will be appreciated that I have provided a lock which is extremely simple yet sturdy in construction, one which is of relatively thin dimensions, and one which in view of the few number of elements readily lends itself to machine assembly.

While I have shown but a single embodiment of my invention it is to be understood that I do not wish to be limited to the details of construction disclosed, since modifications

thereof may be resorted to without departing from the spirit of the invention.

What I claim is:

1. A lock comprising a cover plate, a key operable elongated tumbler slidable against the back of the cover plate, and a spring pressed draw-bolt movable over the back of the cover plate enclosing the tumbler, said draw-bolt having longitudinal flanges, the edges of which engage the back of the cover plate and struck up lips which project toward the cover plate spaced from one of the flanges, said struck-up lips and flange serving to guide the tumbler in its movements when operated by a key. 70

2. A lock according to claim 1 having spring means disposed between the guiding flange and the tumbler urging the latter against one of the struck-up lips. 80

3. A lock comprising a cover plate, a tumbler slidable against the back of the cover plate, a spring pressed draw-bolt having longitudinal flanges the edges of which slidably engage the back of the cover plate, struck-up lips on the draw-bolt projecting toward the cover plate and spaced from one of the flanges and providing therewith guiding means for the tumbler, a spring between the guiding flange and the tumbler urging the latter against one of the struck-up lips, said draw-bolt enclosing the tumbler, the tumbler spring, and the draw-bolt spring, and providing with the back of the cover plate a housing for said elements. 95

In witness whereof, I have hereunto signed my name.

MITCHELL LEVENTHAL.
